HEEL FOR LADY'S SHOE

Ivo Barbaresi, Florence, Italy, assignor to Salvatore Ferragamo S.p.A., Florence, Italy

Filed Dec. 31, 1968, Ser. No. 15,163

Claims priority, application Italy July 9, 1968

Term of patent 7 years

Int. Cl. D2—04

U.S. Cl. D2—325

FIG. 1

FIG. 2

FIG. 3

FIG. 4

FIG. 1 is a side elevational view of a heel for a lady's shoe, showing my new design;

FIG. 2 is a bottom plan view thereof;

FIG. 3 is a rear elevational view with the heel tilted forward; and

FIG. 4 is a perspective view from above the heel.

I claim:

The ornamental design for a heel for lady's shoe, substantially as shown.
